UNITED STATES PATENT OFFICE

2,178,372

GAS GENERATOR

Kenneth W. Goulet, Detroit, Mich.

Application July 27, 1938, Serial No. 221,582

4 Claims. (Cl. 23—282)

The present invention pertains to a novel gas generator, particularly for producing hydrocyanic acid gas for fumigating buildings, and consists of improvements and simplifications of the 5 apparatus shown in my co-pending application, Serial No. 208,839, filed May 19, 1938.

The present invention has advantages in addition to those described in the co-pending application, among which is the elimination of filters at 10 the several gas outlets for removing the liquid acid content in the gas. These filters are eliminated by the use of a funnel for holding the solid reagent and against which the acid content condenses before reaching the outlet. The condensate flows from the surface of the funnel back into the liquid receptacle.

As in the previous application, a diaphragm is employed with means for puncturing it in case a dangerous pressure is developed in the apparatus. In the present invention, the diaphragm is connected by means of a rod to a movable closure 20 at the outlet of the funnel, whereby said outlet is governed by the gas pressure. In addition, a manual means is provided for operating the rod, if necessary or desired.

The invention also solves the problem of pressure gauges. Ordinary gauges are subject to corrosion by the gas, or if specially made of non-corroding material, are very expensive. In this 30 invention, the above mentioned rod is calibrated and cooperates with a fixed part of the apparatus to indicate the pressure, since the rod is actuated by the diaphragm.

Another feature of the invention resides in surrounding the acid receptacle with a gas-absorbing as well as heat-insulating material to render harmless any leakage from the receptacle. The same material is also effective in case of breakage of the receptacle. Powdered charcoal is very 40 appropriate for this purpose.

The invention is fully disclosed by way of example in the following description and in the accompanying drawing, in which

Figure 1 is a vertical section of the device;

Figure 2 is a side elevation;

Figure 3 is an enlarged section on the line 3—3 of Figure 1, and

Figure 4 is a plan view.

Reference to these views will now be made by use of like characters that are employed to designate corresponding parts throughout.

The body of the apparatus includes a metal drum or cylinder 1 having an elevated or false bottom 2. On the bottom 2 is mounted a crock

3 of suitable ceramic material, extending to the top of the drum as may be seen in Figure 1.

The side wall of the crock 3 is spaced from the wall of the drum, and the space is filled with a suitable heat-insulating and gas-absorbing material 4, such as powdered charcoal, for a purpose that will presently be described. On the top of the drum and the crock is mounted a cover plate 5 preferably provided with a rubber gasket 6. For securing the cover to the drum, the latter has an angle ring 7 secured around its upper edge, with bolts 8 extending therefrom through the edge of the cover and held by wing nuts 9.

The internal parts presently to be described are obviously assembled before the cover is applied. On the upper edge of the drum and crock is mounted a flat ring 10 from which hangs a curved lip or channel 11 extending into the crock. In this device is mounted a funnel 12 having a band 13 secured around its upper edge. The 20 band, which may be regarded as an integral part of the funnel, rests in the bottom of the channel 11 for supporting the funnel. The band has two peripheral rows 14 and 15 of perforations, one above and the other below the upper edge of the funnel. The cone of the funnel is so shaped as to leave a space 16 from the free edge of the channel and in communication with the perforations, for a purpose that will presently appear.

The cover is formed with an opening 17 over which is secured a diaphragm 18. Over the diaphragm and on the cover is secured a poison gas filter generally indicated by the numeral 19. Through the top of the filter passes, rather loosely, a vertical rod 20 extending also through the diaphragm and the opening 17 approximately to the bottom of the funnel 12. The rod is secured and sealed to the diaphragm by an appropriate clamping means 21. The lower end of the rod carries an upright conical gate or closure 22 adapted to close the discharge opening 23 in the bottom of the funnel.

The portion of the rod 20 passing through the top of the filter 19 is calibrated at 24 to cooperate with the top of the filter to provide a gauge or indicator for the pressure on the diaphragm 18. The upper end of the rod 20 is formed with a handle 25 to which is attached one end of a lever 26 fulcrumed at 27 on the filter 19, for manually raising or lowering the rod 20 and gate 22.

In the cover 5 is formed a porthole 28, with a lid 29, through which lumps 30 of a reagent such as sodium cyanide can be dropped into the funnel. By manipulation of the rod 20, the lumps are dropped into a liquid reagent 31 such as sulphuric 55

acid contained in the crock 3. Examples of these reagents are given in my co-pending application. The gas thus generated flows through the space 16, the perforations 15, the space 32 between the band 13 and the side wall of the channel 11, and through the perforations 14 to the under side of the cover 5.

The filter includes a base ring 33 secured over the diaphragm and to the cover 5 by screws 34. To the vertical sides of the ring 33 are fastened 10 perforated cylinders 35 and 36, between which is packed suitable filtering material 37. A hood 38 is mounted over the perforated cylinders and secured thereto by any suitable means such as 15 welding. The hood extends downward approximately to the top of the base ring 33 to prevent rain from entering the perforations. The perforated cylinders are fastened to the ring 33 by a series of screws 39 which, in conjunction with 20 the series of screws 34, permits dismantling of the filter and access to the material 37 for replacement of the same.

In the cover are mounted a desired number of nipples 40 to which are connected hose lines 41 25 leading to the space to be fumigated, as described in my co-pending application. The gas flowing through the perforations 14 enters the nipples and hose lines and also exerts pressure against the diaphragm 18. Moisture carried upward from 30 the liquid 31 with the gas condenses on the various surfaces it encounters, particularly the outside of the funnel 12 from which it drains back into the crock. Whatever liquid condenses in the channel 11 is drained out through curved tubes 35 or traps 11' so bent as to prevent direct flow of gas therethrough from the crock into the channel.

The diaphragm expands according to the pressure developed by the liberated gas, moving the rod 20 proportionally. The pressure is indicated, 40 at least approximately, at the calibrations 24.

The diaphragm 18 as well as the metal and other parts contacting with the gas are of such a composition as to resist corrosion by the gas. The invention thereby provides an effective and inexpensive pressure gauge which surpasses conventional gauges inasmuch as the latter do not resist the action of the gas, or if constructed of special materials to resist such action, are too expensive. The diaphragm 18 is so constructed 45 and adjusted that the gate 22 closes the opening 23 and uncovers the opening at the desired limit pressures in the apparatus. The rod 20 and the gate 22 may be moved manually, if desired, in either direction by the lever 26.

The invention also includes a safety device for puncturing the diaphragm and releasing the gas in case the gas pressure comes close to the explosion point. For this purpose, one or more stems 42 threaded through the top of the hood 38 carry piercing members such as blades 43 above the diaphragm. The diaphragm expands sufficiently to engage the members and to be punctured by them when the pressure nears the danger point. The space above the diaphragm 60 communicates with the annular filter, through which the released gas escapes to the atmosphere in a harmless condition.

Windows 44 and 45 are provided in the crock and in the drum for showing the level of the liquid 70 in the crock. The liquid is poured into the crock after the cover has been applied, through the porthole 28 with the gate 23 open and before the solid matter 30 has been dropped into the funnel. After pouring in the liquid, the gate 23 is 75 lifted by hand, and the lumps are dropped into

the funnel. The rod 20 and gate 23 are held in raised position by a slotted plate 46 slidably mounted on the hood 38 and engagable in a restriction 47 in the rod, as shown in Figure 1. The action is started by opening the gate manually, after which it is more or less automatic, or controlled from the lever 26, as previously described. 5

Two outlet connections 48 and 49 are provided in the bottom of the crock and extend through the false bottom 2, as illustrated in Figure 1. 10 These are accessible through a slide door 50 in the wall of the drum and below the false bottom 2. The purpose of these fittings is fully disclosed in the co-pending application.

Any leakage of gas over the top of the crock is 15 absorbed by the powdered charcoal 4 which also serves a similar purpose in case the crock should crack.

Although a specific embodiment of the invention has been illustrated and described, it will be 20 understood that various alterations in the details of construction may be made without departing from the scope of the invention, as indicated by the appended claims.

What I claim is:

1. A gas generator comprising a fluid receptacle, a cover therefor, a container for solid material suspended in the top of said receptacle and having an open top and bottom, a movable closure for the bottom opening of said container, an outlet from said cover, and means of communication from said receptacle to said outlet around said container, said cover having an opening, a diaphragm over said opening, a rod fastened to said closure and diaphragm, and puncturing means supported over said diaphragm and so constructed and arranged that the diaphragm upon expanding beyond a certain point strikes against said puncturing means and punctures it 30 self thereon by the force of its own expansion. 35

2. A gas generator comprising a fluid receptacle, a cover therefor, a container for solid material suspended in the top of said receptacle and having an open top and bottom, a movable closure for the bottom opening of said container, an outlet from said cover, and means of communication from said receptacle to said outlet around said container, said cover having an opening, a diaphragm over said opening, a rod fastened to 45 said closure and diaphragm and extending beyond said diaphragm, and pressure indicating means associated with said rod, and puncturing means supported over said diaphragm and so constructed and arranged that the diaphragm upon expanding beyond a certain point strikes 50 against said puncturing means and punctures itself thereon by the force of its own expansion. 55

3. A gas generator comprising a fluid receptacle, a cover therefor, a container for solid material suspended in the top of said receptacle and having an open top and bottom, a movable closure for the bottom opening of said container, an outlet from said cover, and means of communication from said receptacle to said outlet around said container, said cover having an opening, a 60 diaphragm over said opening, a rod fastened to said closure and diaphragm, a gas filter mounted around the edge of said diaphragm and clamped to said cover to secure the diaphragm, and puncturing means supported by said filter over said diaphragm and so constructed and arranged that the diaphragm upon expanding beyond a certain point strikes against said puncturing means and punctures itself thereon by the force of its own expansion. 65

4. A gas generator comprising a fluid receptacle, a cover therefor, a container for solid material suspended in the top of said receptacle and having an open top and bottom, a movable closure for the bottom opening of said container, an outlet from said cover, and means of communication from said receptacle to said outlet around said container, said cover having an opening, a diaphragm over said opening, a rod fastened to said closure and diaphragm, a gas filter

mounted around the edge of said diaphragm and clamped to said cover to secure the diaphragm, and puncturing means adjustably supported by said filter over said diaphragm and so constructed and arranged that the diaphragm upon expanding beyond a certain point strikes against said puncturing means and punctures itself thereon by the force of its own expansion. 5
